[57] CLAIM

The ornamental design for a beverage cart, as shown
and described.

DESCRIPTION

FIG. 1 is rear perspective view of a beverage cart show-
ing my new design, the broken lines are for illustrative
purposes only and form no part of the claimed design;

FIG. 2 is a top plan view thereof.

FIG. 3 is a bottom plan view thereof.

FIG. 4 is a rear elevational view thereof.

FIG. 5 is a front elevational view thereof.
FIG. 6 is a side elevational view thereof; the opposite
side being a mirror image.
